CHIROPEDIC PHOTOGRAPHY PRACTICE

Albert Vogeli, Toledo, Ohio

Application May 19, 1948, Serial No. 27,853

1 Claim. (Cl. 250—50)

1

This invention relates to photography, and more particularly to different views of an object at the identical support position therefor.

This invention has utility when incorporated as a chiropedic platform incidental to obtaining foot X-ray views wherein the patient retains the original stance, the energy source or tube position is undisturbed. This is herein accomplished by providing a turn-table or swivel base for the platform. The patient accordingly remains standing at the same position adopted for taking a first view, say of the left foot; then without disturbing the patient, the operator merely turns the platform, say 180° to have the right foot in viewing for the energy source. In the instance of a pocket exposing a portion only of the film for the left foot exposure, such film may be rotated top edge down to bring the unexposed film portion to project above the platform and properly back of the right foot for the next exposure. Notwithstanding that the platform has been turned, the patient retains the original standing position so that the patient's body load is transmitted to the respective feet in like manner still retained for the left foot as the right foot be subject to exposure for an X-ray picture thereof.

Referring to the drawings;

Fig. 1 is a plan view of a turn-table platform chiropedic X-ray device of the invention embodiment;

Fig. 2 is a partial medial vertical section of the platform of Fig. 1;

Fig. 3 is a side elevation of the platform from the left of Fig. 1;

Fig. 4 is a fragmentary plan view of film holder clamping fork;

Fig. 5 is a section in the region of the line V—V, Fig. 1, with showing of lift position for the film; and

Fig. 6 is a plan view, partly broken away, of the film pocket of Fig. 5.

The device embodiment of the invention is herein shown as comprising a circular base 1 having a central opening 2. An angle guide or shield near the outer top edge of the base 1, has an upright leg 3 and therefrom a lower outwardly extending leg or flange 4 directly mounted on the upper side of the base 1 with a pair of cross straps 5 as reinforcement extending at 90° apart diameters therefrom to cross centrally of the opening 2 and there having an opening 6 to receive an externally threaded stem 7.

A cylindrical shell or housing 8 is of internal diameter to rise outside of and just clear from contacting the leg 3 of the base angle. The shell 8, spaced upwardly from its lower free edge 9 has on its inner side a flange or angle ring 10 with an inwardly extending track 11 against the lower face of which may rise rollers 12, say

2

three in number and equally spaced in brackets 13 mounted on the base 1 adjacent the inner face of the flange leg 3.

Weld anchored with the track 11 is a pair of diametrically extending metal straps 14 centrally crossing to have mounting for the stem 7. Accordingly, as the stem 7 protrudes thru the opening 6, a pair of nuts 15 on the protruding lower portion of the stem 7 serve to anchor the shell 8 with the base 1.

The shell 8 has rising on its inner face from the ring 10 weld assembled metal straps 16 welded to a downwardly extending leg 17 of an angle ring having an outwardly extending leg 18 at the top of the shell 8.

The leg ring 18 provides anchored mounting for a top disk or platform 19 having intersecting diameter markings 20, 21, at right angles. Along the diameter 21 from its intersection with the diameter 20 is a slot 22 thru the platform 19 providing entrance to a film pocket. One side of this pocket has a flange top 23 anchored to the underside of the platform 19 alongside the slot 22. From this flange 23 is a depending pocket side 24 to a ledge 25.

The opposite side of this pocket from the slot 22 has from the ledge 25 a wall portion 26 gradually extending away from the wall 24 to an upright portion 27 to a flange 28 mounted at the under side of the platform 19. These pocket walls 24, 26, 27, have a lining or internal facing, as of lead 29, opaque or serving as an effective shield or screen against X-ray leakage to a film therein.

The platform 19 has a slight overhang relatively to the shell or housing 8. Projecting from the shell 8 and under the overhang, near the platform 19 approximating alignment with the marking 20 is a pull knob 30 on a rod 31 normally urged by a compression helical spring 32 to have its spaced ends 33 rest snugly against an X-ray film 34 which may freely slide down into the pocket in passing thru the slot 22. Normally, say for half the film width, the film 34 may lodge against the ledge 25. The shield or screen 29 is of extent from the pocket to come within about $\frac{3}{8}$ " of the top face of the platform 19. The pressure action of the spring 32 is sufficient to position the film 34 against the wall 24 to maintain constant focal distance therefor. Furthermore, other than position against the ledge or offset 25 may determine the extent to which the film 34 descends, as by the clamping action of the spring 32, or for definite position, 55 supplemented by a filler 35 inserted in the pocket to space the film 34 from the ledge 25 a desired distance.

Spaced from and parallel to the slot 22 is a second slot 36. Fixed with the underside of the platform 19 and extending from the slot 36 are

bracket elements 37 from a wall 38 terminating in a pair of opposing end channels 39 as guide means for an X-ray opaque wall pocket or holder having a top flange 40, a main descending side wall 41 therefrom to an inclined bottom 42 at an upturned flange 43 as a channel to receive the lower edge of a film 44 placed therein and to be directed by side grooves 45 from the wall 41 as riding upwardly from the guides or channels 39.

A blanking-out or shield portion 46 may be placed over a portion of the film 44, thereby to protect it from exposure and conserve for a different picture subsequent use prior to the development of the film.

Approximately in the line 20 at the region of its intersection with the slot 38, is a recess 47 in the top of the platform 19 leading to the slot 38. There is thus provided a finger or finger-nail catch region to take hold of the flange 40 in order to lift the pocket to have the film brought above the platform 19 into an exposure position.

In this ascent of the film in the pocket, the pocket side 41 has riding against its back portion a pair of arms or fork tines 48 of a plunger rod 49 thrust by a helical compression spring 50. Diametrically from the pull knob 30, is a second pull knob 51, the latter being fixed with the rod 49. At the full lift or exposure position for the film 44 as lifted by the flange 40, the spring 50 causes the fork to slide against the face 42 and lodge under the intersection of the face 42 with the ledge 43, in thus stabilizing an untilted holding position for the film 44 in the lifted pocket 41, 42, 43, 45. Upon exposure of the film, the holder may be allowed to drop down into the slot 36 by pulling out the knob 51. As the descent is completed, the knob 51 is released.

Energy source or X-ray equipment 52 may be disposed in proper focus proximity to the platform 19, say in the region of the line 20 extended for a side view of the full left foot of a patient standing on the platform 19, with the left foot on the side of the slot 22 away from the slot 36, and the right foot close to the slot 22 on the side of the slot 22 toward the slot 36. As so positioned, say one-half of the film 44 may be upwardly projected or in its normal position between the feet of the patient. With the patient thus standing in a normal position, the operator may take a view say in the straight position as suggested toward the film 34.

The pocket at the slot 36 has its descent limit at a ledge 52, altho the flange 40 may also provide a down limit.

The platform 19 is a deck of a turntable antifrictionally supported by the rollers 12. The extent of the base 1 is slightly radially outward from the housing or shell 8. Upon the side of the shell 8, say in the region of the knob 51, there is a slideway bracket 53 having a compression helical spring 54 therein to thrust a pin 55 downward to have it register with a recess 56 in the base 1. These recesses may be at different positions, say every 45°. With the pin in register with a recess 56, for release, an eye 57 integral with the pin 55 may be lifted as to the bracket 53, thereby to clear the pin of the recess 56. The operator may then turn the platform 19 with the patient still standing in the same position thereon. In the instance of say 180° shifting to a diametrical recess 56 from that at which the initial exposure was taken on the film 34 in the slot 22, the other or right foot of the patient, as still standing in

the same position, is now toward the energy source 52. Then film 34 as say half projecting from the slot 22 and having thereon the exposure for the left foot of the patient, may now have its top edge turned into the pocket as shown by the arrows 58 (Figs. 1, 3). There is thus left projecting above the plane of the platform 19 and between the feet of the patient, the other or until-now-unexposed portion of the film 34. Accordingly now all is in readiness for the second exposure or for the right foot on the same film with the left foot. Edgewise orienting of the film 44, as shown by the arrows 58 (Fig. 3), has the feet on the developed film bottom to bottom, but the toes of one foot are under the heel of the other. Inasmuch as the patient has remained standing in the same position throughout, there is advantage for the chiropodist of unchanged stance as between the feet of the patient.

Besides this full half turn for the platform 19, as in the instance of taking different feet of the same patient, definite other angles may be taken, without occasion to shift the energy source 52. However, in the event there be other than a horizontal direction sought from the energy source, such source may be adjusted in its mounting 59. This control or manipulation may extend not only as to films in the slot 22, but also to films in the slot 36.

What is claimed and it is desired to secure by Letters Patent is:

A chiropody X-ray photograph patient-supporting turntable platform having a diametrically directed slot in its top, a support for the platform comprising a base, an annular series of rollers mounted on the base, an endless housing forming a skirt depending from the platform and extending toward the base to conceal the rollers, an endless track fixed with the inner side of the skirt to ride on the rollers and coast thru the skirt to carry the platform antifrictionally on the base, centering means extending axially from the base and having connection with the track to hold the skirt spaced from the rollers, a pocket fixed with the platform slot and extending toward the centering means, said pocket being clear of the base and movable with the platform relatively to the base, said pocket providing a seat adapted to position an X-ray film to expose a portion thereof outward from the slot whereby a patient at a single stance astride the slot may have one foot between such film portion and an X-ray energy source, with opportunity for the patient to be repositioned by rotating the platform half way around to place the otherwise unshifted patient in the same stance to expose the other foot to the same undisturbed energy source to be taken by a film portion thus exposed from the other side of the film pocket in its rise therefrom opposite to the exposure for the one foot.
